H. J. Behrens,

Wrench.

No 13,597.

Patented Sep 25, 1855.

inventor:
H. J. Behrens

UNITED STATES PATENT OFFICE.

H. J. BEHRENS, OF NEW YORK, N. Y.

WRENCH.

Specification of Letters Patent No. 13,597, dated September 25, 1855.

To all whom it may concern:

Be it known that I, H. J. BEHRENS, of the city, county, and State of New York, have invented a new and useful Improvement 5 in Wrenches for Turning Screw-Nuts; and I do hereby declare the following to be a full, clear, and exact description thereof, in which—

Figure 1, is a side view of the device.

10 My improvement is for the purpose of cheapening the article below the price of the screw or rack wrenches now in common use, while it is made to hold as powerfully as they do and is easily worked with one 15 hand, a feature of great importance in practice.

I am aware that rack wrenches have been made and used a long time. I am also aware that wrenches have been made with 20 smooth bars like mine, illustrations of which are shown in *Prechtles Technological Encyclopedia*, where a wedge is shown attached to the movable jaw to bind it to the bar driven forward by a lever grasped in 25 the hand. A wedge has also been similarly used driven with a hammer to fasten the movable jaw. The objections to these several devices are that they are found not to readily fasten the jaw, to unfasten only 30 with considerable exertion, and to be very liable to slip when much strain is put upon the wrench for the obvious reason that the whole force to hold the jaw is derived from the friction of the parts upon each other and 35 the key or wedge having the same amount of friction upon the jaw that it has upon the bar is easily moved along with it without any additional binding when greater strains are brought upon the tool so that for 40 every addition of strain upon the wrench a corresponding driving of the wedge is required which if it does not greatly exceed the resistance will allow the jaw to slide. These disadvantages I obviate by employing 45 an eccentric the periphery of which is serrated and hardened so as to produce the maximum of friction upon the bar while it

is hung on a pin in the jaw so as to turn with the minimum of friction there. Thus when the jaw is pressed back by the strain 50 there is but a small amount of friction upon the eccentric to carry it back while its serrated periphery tenaciously holds upon the smooth bar, increasing its holding power with each increase of strain and when the 55 strain is removed allowing an easy and expeditious release so that the jaw can be moved back and forth by one hand.

The construction is as follows: *a* is a square smooth bar having a stationary jaw 60 at one end and a sliding jaw *b* of common form sliding on the bar. This jaw has on its rear side above a bearing for the pivot *d* of the eccentric *c*. This eccentric by turning bears with its periphery upon the 65 bar and the part of the periphery which comes in contact with the bar is serrated so as to insure its hold thereon. There is a thumb piece projecting up from the bar at *e*, between which and the jaw there is a 70 spring *i* which forces down the eccentric upon the bar when it is not pressed back by the fingers. The pin that holds the eccentric to the jaw is made to project as seen in Fig. 2, so as to give a hold to draw the 75 jaw back by. This is necessary when the two jaws are closed together and also to enable me to move the jaw with one hand at all times with facility. This pin is loose and can be slid through so as to come flush 80 with the side in places where it would be an obstacle.

Having thus fully described my improved wrench and pointed out its variation from what before has been done what I claim is— 85

The employment of an eccentric toothed on its periphery and held down by a spring as described in combination with the smooth bar wrench in the manner and for the purpose herein set forth.

HENRY J. BEHRENS.
